US00D597410S

(12) **United States Design Patent**
Carmody et al.

(10) **Patent No.:** **US D597,410 S**
(45) **Date of Patent:** **** Aug. 4, 2009**

(54) **COMBINED BOTTLE AND CAP**

(75) Inventors: **Suzanne M. Carmody**, Cranston, RI
(US); **Aidan Petrie**, Jamestown, RI
(US); **Daniel Nelsen**, Providence, RI
(US); **Margaux Boyaval**, Pascoag, RI
(US)

DESCRIPTION

FIG. 1 is a perspective view of a combined bottle and cap showing our new design; the broken lines, showing a centering recess in the cap, forms no part of the claimed invention; FIG. 2 is a front view thereof; the rear view being a mirror image thereof;

FIG. 3 is a left side view thereof; the right side view being a mirror image thereof;

FIG. 4 is a top view thereof; the broken lines, showing a centering recess in the cap, forms no part of the claimed invention; and,

FIG. 5 is a bottom view thereof; the broken lines, showing a centering recess in the bottom of the bottle, forms no part of the claimed invention.
